LATHE

Max A. Lehmann, Richmond Heights, Mo., assignor to Lehmann Machine Company, St. Louis, Mo., a corporation of Missouri

Application November 20, 1935, Serial No. 50,705

2 Claims. (Cl. 82—31)

This invention relates to lathes and more particularly to the sliding tailstocks thereof. It has for its principal object to provide for lubricating the ways along which the tailstock slides. Other objects are simplicity and cheapness of construction and compactness of design. The invention consists in the lathe tailstock and in the construction, combinations and arrangements of parts hereinafter described and claimed.

10 In the accompanying drawing, which forms part of this specification and wherein like symbols refer to like parts wherever they occur,

Fig. 1 is a side view of the rear end portion of a lathe provided with a tailstock embodying my 15 invention,

Fig. 2 is a horizontal section on the line 2—2 of Fig. 1, with the tailstock base and supporting ways therefor shown in plan,

Fig. 3 is a vertical cross-section on the line 20 3—3 of Fig. 2,

Fig. 4 is a fragmentary cross-section on the line 4—4 of Fig. 2,

Fig. 5 is a vertical cross-section on the line 5—5 of Fig. 2; and

25 Fig. 6 is a vertical longitudinal section on the line 6—6 of Fig. 2.

The accompanying drawing illustrates the tailstock end of an ordinary lathe comprising a bed 1 provided at its upper side corners with longitudinal ways 2 and 3, respectively, a base member 4 slidable along said ways, a tailstock 5 mounted on and secured by bolts 6 to said base member, a dead spindle 7 mounted in said tailstock, a hand wheel 8 for adjusting said spindle 30 axially in said tailstock, and a handle 9 for locking said spindle in the desired position of adjustment. The tailstock is slid along the ways of the lathe bed by means of a pinion 10 that meshes with a rack 11 on the lathe bed and is 35 fixed to a shaft 12 that is journaled in a bracket 13 fixed to the tailstock base and is provided with a suitable operating arm 14. As shown in the drawing, the contacting surfaces of the way 2 and the tailstock are disposed in a horizontal 40 plane; and the way 3 is of substantially inverted V-shape cross-section and cooperates with a similar V-shape groove 3a provided therefor in the underside of said tailstock base. The lathe construction thus far described is well known 45 and it is unnecessary to illustrate it in detail.

As shown in Fig. 2 of the drawing, the tailstock base 4 comprises a frame having spaced parallel side frame members 15 and 16 that rest upon the ways 2 and 3, respectively, of the lathe bed and 50 are integrally connected by end frame members

17 and by spaced intermediate cross frame members 18 and 19. Formed in the top surface of the tailstock base or supporting frame is a lubricant containing groove that is closed at its top by the tailstock 5. Said lubricant groove has a portion 20, which extends longitudinally of the side frame member 16 of the tailstock base 4 from a point adjacent to the rear end thereof to a circular recess or pocket 21 located opposite the adjacent end of the intermediate cross frame member 19 of said frame, and a portion 20a, which extends longitudinally of said cross frame member from the recess or pocket 21 in the side frame member 16 to the side frame member 15 where it terminates in a pocket or recess 22. The tailstock base is provided with discharge passageways 23 that lead downwardly from the pocket 21 to the opposite sides of the V-shaped groove 3a in the underside of said tailstock base; and the pocket 22 is likewise provided with outlet passageways 24 that lead downwardly therefrom to the portion of the underside of said base that rests on the way 2. Mounted on the tailstock base or supporting frame 4 is a cup or other suitable reservoir 25 for lubricant that communicates with the rear end of the portion 20 of the lubricant groove through a passageway 26 in said frame.

By the arrangement described, lubricant flows from the reservoir 25 carried by the tailstock base 30 into the portions 20 and 20a of the lubricant groove therein and thence through the holes in the bottoms of the pockets or enlarged portions 21 and 22 of said groove base to the supporting ways and is distributed along said ways and the 35 portions of the base cooperating therewith when the tailstock is moved along the lathe bed. The lubricant groove is easily formed in the tailstock base, and the entry of dust or other foreign matter into said groove is prevented by the tailstock 40 which forms a cover therefor.

What I claim is:

1. In a lathe, a bed provided with spaced parallel ways and an open-work supporting frame comprising side frame members slidably supported on the respective ways and connected by cross-frame members, said frame having a lubricant containing groove in its upper surface that extends longitudinally of one of said side frame members and thence along one of said cross-frame members to the other of said side frame members, said groove having enlarged pocket portions located in the respective side frame members opposite the ends of said cross-frame member, said side frame members having dis- 50 55

charge passages therein that lead downwardly from the enlarged pocket portions therein to the respective slideways.

5 2. In a lathe, a bed provided with spaced parallel ways, an open-work tailstock supporting frame comprising side frame members slidably supported on their respective ways and integrally connected by end and intermediate cross-frame members, said frame having a lubricant containing groove in its upper surface that extends longitudinally of one of said side frame members and thence along said intermediate cross-frame

member to the other of said side frame members, said groove having enlarged pocket portions located in the respective side frame members opposite the ends of said intermediate cross-frame member, said side frame members having discharge passageways that lead downwardly from the enlarged pocket portions thereof to the respective slideways, and a reservoir for lubricant mounted on and movable with said frame for supplying lubricant to said groove. 5 10

MAX A. LEHMANN.
